UNITED STATES PATENT OFFICE.

VERNON ROYLE, OF PATERSON, NEW JERSEY.

GEARING MECHANISM FOR TUBING MACHINES.

Application filed October 17, 1919. Serial No. 331,395.

This invention relates to gearing mechanism for tubing machines, and has for its object to provide apparatus of this character which includes means for driving the screw 5 or plodder at different speeds from a constant initial speed, to adapt it for operating upon materials of different consistencies and in connection with the manufacture of articles of different sectional sizes and shapes. 10 Another object consists in providing such an apparatus with an improved bed and with means for accommodating motors of different sizes.

Another object consists in providing such 15 an apparatus with means for adjusting the power shaft bearings, both horizontally and vertically, in order to establish perfect alinement.

Another object consists in providing such 20 an apparatus with means for adjusting the drive shaft bearings, both horizontally and vertically, in order to establish perfect alinement.

A further object consists in providing cer- 25 tain improvements in the form, construction and arrangement of the several parts whereby the above named and other objects may be effectively attained.

In the ordinary apparatus of this kind, 30 the bed of the machine is cast in a single piece of metal and this is not only a difficult and expensive operation, owing to the size of the part; but, a bed of this kind is very liable to warp and very difficult to keep 35 exactly level. Furthermore, it has not been customary to provide ample space for properly locating on the bed an electric drive motor, owing to the undesirability of increasing the area of the bed to this extent.

40 Again, the standards and bearings for supporting the shafts and gears have not been adequately provided with satisfactory features of adjustment for properly alining the parts.

45 These conditions have given rise to a great deal of difficulty in the manufacture, shipment and installation of such apparatus for the reason, among others, that it entailed a great deal of painstaking labor to properly 50 place the various parts on the bed and aline them with each other; and because of the fact that, after a machine had been properly set up and alined, it would not retain this alinement during shipment, so that, when received by the user, it would have to be re-set and realined in order to function to the best advantage. Indeed, it frequently happened that a machine which had been perfectly set up at its place of manufacture, when received by the purchaser would not even operate, owing to misalinement.

These machines have been and are still designed to operate upon materials of very different consistencies and I have found that different materials require a different operating speed of the plodder or screw. This requirement has not been adequately satisfied in former machines.

It is also a fact that these machines are used in heavy work and it has heretofore been the custom to make them of very considerable size and weight in order to enable them to stand up under their service requirements, with resulting waste of material and floor space.

In designing the machine which constitutes my present invention, I have had in mind to obviate these limitations and disadvantages of former machines. The bed of my improved machine is built up from relatively light individual longitudinal and cross members composed of hollow metal, these members being suitably bolted together. This makes a bed which is light, very rigid, relatively simple and cheap to manufacture, and which may be easily increased or reduced in size by changing the dimensions of one or more of the individual members. The separability of the parts enables them to be stored in a small space, and this is a consideration of importance to a manufacturer who is required to keep stock on hand. Finally, and perhaps most importantly, I have found that a built up bed of this character is exceedingly rigid and very easy to level, and that it does not get out of true during shipment or warp in any manner.

I also provide the bed with superimposed cross rails that may be secured thereto by bolts and project laterally therefrom. These rails are adapted for the reception of an electric motor and enable the latter to be placed in any desired position with respect to the remainder of the apparatus, without, in effect, increasing the size or materially increasing the weight of the

bed. As a result of these provisions, I have a bed which is eminently satisfactory in overcoming the objections noted and this constitutes an important practical feature of my invention.

As means for supporting the shafts and gears, I use standards of inverted V form and these are very strong and rigid, though light and compact. These standards are bolted to suitable parts of the bed and are adapted to receive on their sloping sides brackets and bearings which may be secured thereto in any desired position. Certain of the bearings are loosely fitted in their brackets and are flanged to permit them to be adjustably secured therein. I thus provide an arrangement in which the shaft bearings are, in effect, movable horizontally and vertically to an ample extent for mounting the shafts and gears carried thereby in suitable alignment and mesh with their complementary parts. This greatly simplifies and facilitates the operation of setting up and aligning the machine and permits an economy of space; so that it also constitutes an important feature of my invention.

In convenient juxtaposition to the main gear which actuates the plodder, I locate sets of change speed and intermediate gears, which are conveniently movable for effecting communication between the main gear and the driving gear actuated from a source of power. This enables the main gear, and hence the plodder, to be driven at any speed within the capacity of the change speed gears, and so adapts the machine for perfectly satisfactory operation upon varying kinds and consistencies of material, the change from any one speed to another being quickly and instantly accomplished by the mere throwing of a lever. This also enables the apparatus to be readily adapted for use with an alternating current motor, the single constant speed of which might not otherwise be suitable for the machine; and enlarges the field of speed variation in case of the employment of a direct current motor of the variable speed type. This capacity is of prime importance in a machine of this kind and it also constitutes an important feature of my invention.

The foregoing is intended merely as a general statement calculated to set forth certain characteristics of my invention and indicate their importance as applied to this particular art.

A practical embodiment of the invention is represented in the accompanying drawings in which:

Fig. 1 represents a side elevation of the apparatus.

Fig. 2 represents a top plan view of the same, partly broken away.

Fig. 3 represents a rear end elevation of the same.

Fig. 4 represents a section taken in the plane of the line IV-IV of Fig. 1, looking in the direction of the arrows.

Fig. 5 represents a section taken in the plane of the line V-V of Fig. 1, looking in the direction of the arrows.

Fig. 6 represents a detail section taken in the plane of the line VI-VI of Fig. 1, looking in the direction of the arrows.

Fig. 7 represents a detail section similar to Fig. 5, but showing certain parts in different positions.

Fig. 8 represents a detail section similar to Fig. 7, showing certain parts in different positions.

Fig. 9 represents a detail section taken in the plane of the line IX-IX of Fig. 2, looking in the direction of the arrows.

Fig. 10 represents an enlarged detail section taken in the plane of the line X-X of Fig. 11, looking in the direction of the arrows.

Fig. 11 represents an enlarged detail end view, showing the means for adjusting one of the eccentric shafts.

Fig. 12 represents a detail section taken in the plane of the line XII of Fig. 3, looking in the direction of the arrow.

Fig. 13 represents a detail section taken in the plane of the line XIII-XIII of Fig. 1, looking in the direction of the arrows.

Fig. 14 represents a detail section, partly in elevation, taken at right angles to Fig. 13.

Fig. 15 represents a view similar to Fig. 18, showing certain parts in a different position.

Fig. 16 represents a view similar to Fig. 14, showing certain parts in a different position.

Fig. 17 represents a plan view, partly in section, of the bed for the apparatus.

Fig. 18 represents a section taken in the plane of the line XVIII-XVIII of Fig. 17, looking in the direction of the arrows.

Fig. 19 represents a section taken in the plane of the line XIX-XIX of Fig. 17, looking in the direction of the arrows.

Fig. 20 represents a detail top plan view showing a modified form of drive.

Fig. 21 represents a detail vertical section, partly in elevation, of the same.

Fig. 22 represents a detail end elevation of the same.

Fig. 23 represents a detail vertical section, showing a second modified form of drive.

Fig. 24 represents a detail elevation, of a modified form of bearing for the power shaft.

Fig. 25 represents a section taken in the plane of the line XXV-XXV of Fig. 24, looking in the direction of the arrows.

The apparatus is provided with a bed (see Figs. 17 and 19) which consists of a pair of sills 1, 2, which are composed of

hollow metal, and are connected by four cross-bars 3, 4, 5, 6, which are also composed of hollow metal and firmly bolted to the sills. The cross-bar 3 takes the form of an open framework and has a base plate 7 which is designed to support a pedestal 8 (see Fig. 1) that carries the head 9 of the tubing machine. The head 9, and its interior mechanism, including the screw or plodder, constitute no part of my present invention, and hence will not be described herein, as they may be of any well known and approved form.

A shaft 10 (which drives the screw or plodder) projects rearwardly from the head 9, and has a driving member 11 splined thereto; which driving member carries three dogs 12 that engage three lugs 12* on the hub of the main gear 13, for causing the latter to rotate in unison with the shaft 10. A finger 13* on the gear 13 is fitted to enter a notch in the member 11 for centering the parts.

The end of the bed opposite to that upon which the pedestal 8 is mounted, carries a pair of rails 14, that are bolted to the top of the sills 1, 2, and project laterally beyond the sill 1. These rails 14 serve for the mounting of the motor 15 that is calculated to drive the machine. By reason of the fact that the rails project beyond the sill 1, they have the capacity for supporting a relatively large motor without necessitating corresponding enlargement of the bed 35 of the apparatus, which enlargement would tend to make the same cumbersome.

Furthermore, the motor may be bolted to the rails 14 at any desired position in order to aline its shaft with the shaft of the apparatus intended to be driven thereby.

A standard 16, of inverted V shape, is bolted to the cross bar 5, and it is designed to constitute a support for a bearing for the power shaft 17 (see Figs. 1 and 4) that is coupled to the shaft of the motor 15 by a conventional form of coupling 18. A bracket 19 is bolted to one sloping side of the standard 16, which side is flanged in order to provide a relatively broad support for the said bracket. The upper part of the bracket is formed with a flat surface adapted to receive the bearing 20 for the shaft 17, which bearing is bolted to the said surface of the bracket 19. It will be observed that the arrangement just described is such that the shaft 17 may be brought into perfect alinement with the shaft of the motor 15 by adjusting the bracket 19 along the side of the standard 16, and adjusting the bearing 20 laterally on the upper face of the bracket. This adjustment may be made on the bracket and the bearing clamped in position before the parts are drilled to receive the cap screws or bolts used for securing them in place.

A second standard, denoted by 21 (see

Fig. 6) is bolted to the cross-bar 4, and it has a flanged sloping side corresponding to that on the standard 16, to which side a bracket 22, which corresponds to the bracket 19, is made secure. A bearing 23 quite similar to the bearing 20, is bolted to the flanged upper face of the bracket 22, and serves to receive the inner end of the shaft 17. The construction and arrangement of the bracket 22 and bearing 23 provides for them the same facility of adjustment as that which has been described in connection with the bracket 19 and bearing 20, so that both bearings for the shaft 17 may be perfectly true with each other and with the shaft of the motor 15. The shaft 17 may be provided with suitable oil guards 24, and with suitable bearing linings, all of which is well understood by an operative in this industry.

A gear 25 is formed integral with a sleeve 26 that is keyed to the shaft 17, which gear meshes with a larger transmission gear 27, that is mounted on the drive shaft 28 (see Figs. 2 and 4). One end of the shaft 28 is journaled in a bearing 29 that is bolted to the flanged sloping side of the standard 16 opposite to that to which the bracket 19 is secured. The intermediate part of the said shaft is journaled in a bracket 30 bolted to the top of the standard 21 and provided with a loosely fitting flanged bearing 31. The other end of the shaft has an elongated bearing in an inwardly projecting stud 32 that is bolted to the adjacent side of the pedestal 8.

The gear 27 has an elongated bearing 33 that is rotatably mounted on the shaft 28, through the intermediation of a liner 34 (see Fig. 9). This construction tends to obviate any wobbling or side play of the said gear. A clutch mechanism 35, of a conventional form, engages the inner periphery of the gear 27 and has its sleeve 35* keyed to the shaft 28. A lever 36 (see Figs. 4 and 6) for operating the clutch mechanism 35 is pivoted at 37 in a bracket 38 secured to the standard 21, and has a pair of fingers 38* for engaging a groove in the sleeve 35*. It will be seen that when the clutch mechanism is engaged with the gear 27, the latter will be fixed to the shaft 28 and thereby drive the said shaft when power is received from the gear 25 on the power shaft 17. When the clutch mechanism 35 is released from the gear 27, the latter will idle on the shaft 28. The adjustable supporting mechanism for the shaft 17 enables the gear 25 to be brought into and kept in perfect mesh with the gear 27.

A pair of integral gears 39, 40, are keyed for sliding movement on the shaft 28, and constitute a double pinion that serves as a driving gear. The gear 40 is designed to mate with the main gear 13, and the gear 39 is intended to mesh with an idler gear 41.

that is mounted on a stub shaft 42 fixed in the wall of the pedestal 8. The arrangement of the parts just described is such that when the gear 40 is in mesh with the gear 13, the gear 39 is out of contact with the gear 41; and when the gear 39 is in mesh with the gear 41, the gear 40 is out of contact with the gear 13.

Shifting mechanism is provided for sliding the double pinion 39, 40 along the shaft 28, (see Figs. 9, 13, 14, 15, 16). This mechanism includes a stub shaft 43 that is fixed in a bracket 44 secured to the side of the pedestal 8 below the shaft 28. A sleeve 45 is mounted to slide on the shaft 43 and has a yoke 46 fitted to engage the integral gears 39, 40. A rod 47 has one end pivoted to the sleeve 45 and its other end linked to the extremity of an arm 48, the other end of which is keyed to a shaft 49 that is journaled in the bracket 44. A hand lever 50 (see Fig. 1) is fixed to the other end of the shaft 49 for manipulating the same; and it will be understood that when the said lever is pulled in one direction, it will swing the arm 48 so as to slide the sleeve 45 and hence the gears 39, 40, in one direction, while the reverse operation of the lever 50 will impart opposite movement to the said gears.

30 The rod 47 and arm 48 are so arranged that, in either position of the parts just described, the joints of the said rod and arm are in a straight line, or, in other words, on "dead center" so as to establish, in effect, 35 a temporary lock in either position.

An eccentric shaft 51 (see Figs. 10 and 11) has one end journaled in the side of the pedestal 8, as indicated at 52, and the other end mounted in a portion of the bracket 40, as indicated at 53. A sleeve 54 is rotatably mounted on the shaft 51 and has one end fashioned to constitute a gear 55, while another gear 56 is splined to the opposite end of the said sleeve 54. The shaft 51 is so mounted that it may be swung inwardly or outwardly so as to bring the gears 55 and 56 into and out of contact with the gears 13 and 41, respectively.

Means is provided for shifting the shaft 51 and gears carried thereby as just described, which means comprises a hand lever 57 that is bifurcated and pivoted in the lower part of a collar 58 keyed on the extreme end of the shaft 51. The lever 57 carries a tooth 59 that is designed to mate with diametrically opposed sockets 60, formed in a loosely fitting flanged bearing 61 that is secured by screws 61* to the face of the part 53 of the bracket 30. A pair of arms 61 are fixed to the bifurcations of the lever 57, and a pair of retractile coil springs 62 connect the ends of said arms with a cross-head 63 that is secured to an upstanding portion of the collar 58 by a screw 64. As will be readily seen, the action

of the springs 62 will be to normally urge the tooth 59 toward the plate 61, so as to retain it in either of the sockets 60. In order to operate this shifting mechanism, the handle 51 is seized and swung to the right 70 (Fig. 10) in order to disengage the tooth 59 from one of the sockets 60. The lever is then swung laterally with respect to the axis of the shaft 51, and moves the said shaft a half turn until the tooth 59 coincides with the other socket 60. When this last position is reached, the tooth is permitted to enter the socket under the influence of the springs 62. Thus the gears 55 and 56 may be locked in mesh with, or out of 80 mesh with, the gears 13 and 41 respectively.

A second eccentric shaft 65 (see Fig. 6) with its sleeve 66 and gears 67, 68, which said parts correspond with the shaft 51, sleeve 54 and gears 55 and 56 (except that the gear 68 is larger than the gear 56) are mounted in the same manner as the corresponding parts just described. These parts 65, 66, 67, 68, are designed to be actuated so as to bring the gears 67 and 68 into 90 and out of mesh with the gears 13 and 41, and to be locked in either position by mechanism just like that described in connection with the shaft 51; which last named mechanism is denoted collectively by 69. By 95 reference to Fig. 6, it will be noted that the shafts 51 and 65 with their associated parts are mounted on opposite sides of the shaft 28.

From the foregoing description, it will be 100 seen that the main gear 13 may be driven directly from the shaft 28, by shifting the gear 40 into mesh with the said gear 13. The gear 13 may also be driven indirectly from the shaft 28 by shifting the gear 39 into engagement with the gear 41, and shifting the gears 55 and 56 into mesh with the gears 13 and 41, in which case the main gear 13 will be driven at another rotative speed. Finally, the main gear 13 may be driven indirectly from the shaft 28 at a third speed, by keeping the gear 39 in mesh with the gear 41, and by swinging the gears 67 and 68 into engagement with the gears 13 and 41, respectively, while moving the gears 55 and 56 out of engagement with the gears 13 and 41. The three positions of the parts just described are represented in Figs. 5, 7 and 8 of the drawings. This arrangement is of importance since it enables the screw or plodder, which is actuated by the gear 13, to be driven at speeds appropriate to the work to be accomplished.

In case an alternating current motor is employed, it is advantageous to allow the 125 same to attain considerable speed before throwing on the load; and this may be accomplished by actuating the clutch mechanism 35 so as to release the gear 27 from the shaft 28, so that the said gear may at- 130

tain a considerable speed while running free. The clutch 35 may then be urged gently into engagement with the gear and the load taken up with a certain slip at first.

5 The head 9 is provided with the customary steam and water pipes 70, 71, which lead into a chest 72 secured to the top of the head, for the purpose of heating or cooling the latter as may be required. In 10 the present instance, however, I have arranged all the controlling valves 73, 74, 75, 76 on the front side of the chest 72. This makes them convenient to the operator and obviates the necessity of reaching around or 15 over the apparatus, with the consequent danger of being burned.

Referring to the modified form shown in Figs. 20, 21, 22; the base is made shorter and the rails 14 are eliminated together with the 20 motor 15 and its shaft and connected parts. The drive shaft 28 is provided with a stepped belt pulley 77, in place of the gear 27 and its connected parts. This pulley is 25 adapted to receive a belt actuated from a suitable source of power (these parts not being shown) and the speed of rotation of the shaft 28 may be varied by applying the belt to the different faces of the pulley in a well understood manner. A standard 78, 30 which is offset in two directions, is substituted for the standard 16, but, it will be noted that it is arranged to be adjustably bolted to the base, and that it also has a slanting face 79 to which a bracket 80 may 35 be adjustably secured. Thus, this standard also provides means for properly alining the shaft 28. By offsetting the standard 78 in a direction parallel to the length of the machine (as shown in Figs. 20 and 21), I am 40 enabled to make the bed smaller and thereby reduce expense and weight and economize space. This also compensates in part for the length of bed required because of the fact that the stepped pulley 77 is greater in 45 axial length than the gear 27.

Referring to the modified form shown in Fig. 23; fast and loose pulleys 81, 82 are mounted on the shaft 28, in lieu of the stepped pulley 77, and are adapted to be 50 driven by a shiftable belt (not shown) in the customary manner.

In this connection, I use a standard 83, which is like the standard 78 except that it is not offset laterally. This standard may be 55 adjustably bolted to the bed, while a bearing 84 may be adjustably secured to the top thereof, as in the case of the bracket 79.

Referring to the modified structure shown 60 in Figs. 24 and 25, it will be seen that I substitute an integral trussed bearing 85 for the two bearings 20 and 23 (shown in the preferred form) for the purpose of supporting the power shaft 17 that carries the gear 25. This integral element 85 makes a very 65 rigid and steady bearing, and renders it easy

to bore the apertures for receiving the shaft 17 in perfect alinement with each other. As it will be seen by reference to Fig. 25, the truss portion of the element 85 is formed with two longitudinal webs 82*, 85**. The 70 element 85 may be suitably enlarged for the reception of the gear 25 and provide hinge knuckles 85*** for the reception of the usual cover for the said gear.

In setting up the apparatus, it will be 75 seen that, after the bed has been assembled, the standards 16 and 21 may be adjusted to exactly the desired position thereon and bolted in place. The brackets 19 and 29 may also be accurately adjusted on the 80 standard 16 and fastened in place; and the bearing 20 properly adjusted on the bracket 19 and screwed in place. The brackets 22 and 30 may be properly adjusted and secured on the standard 21, and the bearing 85 23 similarly adjusted and fastened on the bracket 22. The flanged bearings 31 and 61 (and that included in the group 69) may also be suitably adjusted and secured in the bracket 30. The motor 15 may be properly 90 located and bolted to the rails 14, which latter may also be located as desired and bolted to the bed. It will be clear that these parts may be adjusted and fixed in any desired or appropriate order and that 95 their construction is such that perfect alinement of the rotating parts may be readily obtained, as mentioned above.

I believe that the operation of the apparatus will be clear to anyone acquainted 100 with this industry, in view of the foregoing description, in which the operation of the several sets of mechanism has been detailed in connection with their description; and I desire it to be understood that various 105 changes may be resorted to in the form, construction and arrangement of the several parts without departing from the spirit and scope of my invention. Hence, I do not intend to be limited to the details herein 110 shown and described, except as they may be included in the claims.

What I claim is:

1. Apparatus of the character described comprising, a screw, a main gear for actuating the screw, a drive shaft, a plurality of sets of change speed gears, and a pinion 115 slidably mounted for engaging the drive shaft with the main gear or with either set of change speed gears.

2. Apparatus of the character described, comprising, a screw, a main gear for actuating the screw, a drive shaft, a plurality of sets of change speed gears, and a pinion 125 slidably mounted on the drive shaft for engaging it with the main gear or with either set of change speed gears.

3. Apparatus of the character described comprising, a screw, a main gear for actuating the screw, a drive shaft, a plurality of 130

- sets of change speed gears, an intermediate gear, and a pinion slidably mounted for moving into and out of mesh with the main gear and the intermediate gear.
5. Apparatus of the character described comprising, a screw, a main gear for actuating the screw, and a plurality of sets of change speed gears radially disposed with respect to the main gear.
10. 5. Apparatus of the character described comprising, a screw, a main gear for actuating the screw, a driving gear, and a plurality of sets of change speed gears, said driving gear and change speed gears being radially mounted with respect to the main gear.
15. 6. Apparatus of the character described comprising, a screw, a main gear for actuating the screw, a plurality of change speed gears radially disposed with respect to the main gear, an intermediate gear, a plurality of change speed gears radially disposed with respect to the intermediate gear, and a pinion slidably mounted for engaging either the main gear or the intermediate gear.
20. 7. Apparatus of the character described comprising, a screw, a main gear for actuating the screw, a plurality of change speed gears radially disposed with respect to the main gear, an intermediate gear, a plurality of change speed gears radially disposed with respect to the intermediate gear, and a double pinion slidably mounted for engaging either the main gear or the intermediate gear.
25. 8. Apparatus of the character described comprising, a screw, a main gear for actuating the screw, a change speed gear radially mounted with respect to the main gear, an intermediate gear, a change speed gear radially mounted with respect to the intermediate gear, and a pinion, the said change speed gears being arranged to be moved radially into and out of engagement with the main gear and the intermediate gear, and the pinion being arranged to be moved longitudinally into and out of engagement with the main gear and the intermediate gear.
30. 9. Apparatus of the character described comprising, a screw, a main gear for actuating the screw, a plurality of change speed gears radially mounted with respect to the main gear, an intermediate gear, a plurality of change speed gears radially mounted with respect to the intermediate gear, and a pinion, the said change speed gears being adapted to be moved laterally into and out of engagement with the main gear and the intermediate gear, and the pinion being arranged to be moved longitudinally into and out of engagement with the main gear and the intermediate gear.
35. 10. Apparatus of the character described comprising, a screw, a main gear for actuating the screw, a driving gear, and a plurality of sets of change speed gears arranged to be brought into and out of mesh with the main gear and engagement with the driving gear for rotating the main gear at 70 different speeds.
40. 11. Apparatus of the character described comprising, a screw, a main gear for actuating the screw, a drive shaft, a set of change speed gears, and a double gear arranged to be slid in different directions for causing the main gear to be driven from the drive shaft through the intermediation of the change speed gears or without the intermediation of the change speed gears.
45. 12. Apparatus of the character described comprising, a screw, a main gear for actuating the screw, a drive shaft, a transmission gear thereon, a power gear meshing with the transmission gear for rotating the same, a set of change speed gears, and a double gear mounted for sliding movement in different directions upon the drive shaft for causing the main gear to be driven directly from the drive shaft or through the intermediation of the change speed gears.
50. 13. Apparatus of the character described comprising, a pedestal, a screw, a main gear mounted on the pedestal for actuating the screw, a driving gear, a plurality of sets of change speed gears mounted on the pedestal, and means for bringing the change speed gears into and out of engagement with the main gear and driving gear.
55. 14. Apparatus of the character described comprising, a pedestal, a screw, a main gear mounted on the pedestal for actuating the screw, a plurality of shafts projecting from the pedestal, a set of change speed gears mounted on each of said shafts, a driving gear, and means for bringing the change speed gears into and out of engagement with the main gear and the driving gear.
60. 15. Apparatus of the character described comprising, a pedestal, a screw, a main gear for actuating the screw mounted on the pedestal, a driving gear, a shaft mounted on the pedestal, a set of change speed gears mounted on said shaft, a stub shaft mounted on the pedestal, an idler gear mounted on said stub shaft, means for bringing the change speed gears into and out of engagement with the main gear and the idler gear, and means for establishing connection between the driving gear and the main gear with and without the intermediation of the idler gear.
65. 16. Apparatus of the character described comprising, a pedestal, a screw, a main gear for actuating the screw mounted on the pedestal, a drive shaft, a shaft mounted on the pedestal, a set of change speed gears mounted on said shaft, a stub shaft mounted on the pedestal, an idler gear mounted on said stub shaft, means for bringing the

change speed gears into and out of engagement with the main gear and the idler gear, and a double sliding gear for establishing connection between the drive shaft and the main gear with and without the intermediate of the idler gear.

17. Apparatus of the character described comprising, a pedestal, a screw, a main gear for actuating the screw mounted on the pedestal, a drive shaft, a transmission gear thereon, a power gear meshing with the transmission gear for rotating the same, a shaft mounted on the pedestal, a set of change speed gears mounted on said shaft, a stub shaft mounted on the pedestal, an idler gear mounted on said stub shaft, means for bringing the said change speed gears into and out of engagement with the idler gear and main gear, and a double gear slidably mounted on the drive shaft for bringing the said drive shaft into driving engagement with either the main gear or with the idler gear.

18. Apparatus of the character described comprising, a screw, a main gear for actuating the screw, a driving gear, a set of change speed gears mounted on an eccentric shaft, and means for moving the said change speed gears edgewise in order to establish connection between the driving gear and the main gear and also to break said connection.

19. Apparatus of the character described comprising, a screw, a main gear for actuating the screw, a driving gear, a set of change speed gears mounted on an eccentric shaft, and means for moving the said change speed gears edgewise in order to establish connection between the driving gear and the main gear and also to break said connection, said last named means comprising a hand lever fixed to said shaft and provided with a tooth, a notched plate independent of said shaft, and means for urging the lever toward the plate.

20. Apparatus of the character described comprising, a screw, a main gear for actuating the screw, a driving gear, a set of change speed gears mounted on an eccentric shaft, and means for moving the said change speed gears edgewise in order to establish connection between the driving gear and the main gear and also to break said connection, said means serving to lock said change speed gears in either position.

21. Apparatus of the character described comprising, a screw, a main gear for actuating the screw, a driving gear, a set of change speed gears mounted on an eccentric shaft, and means for moving the said change speed gears laterally in order to establish connection between the driving gear and the main gear and also to break said connection, said last named means comprising a hand lever fixed to said shaft and

provided with a tooth, a plate independent of said shaft and having diametrically opposed notches, and means for urging the lever toward the plate, whereby said tooth may be caused to enter either notch and said change speed gears may be locked in either position.

22. Apparatus of the character described comprising, a screw, a main gear for actuating the screw, a driving gear, an idler gear, a pair of eccentric shafts mounted one on each side of the idler gear, and means for moving each of said eccentric shafts in a rotary direction in order to establish connection between the driving gear and the main gear and also to break said connection.

23. Apparatus of the character described comprising, a screw, a main gear for actuating the screw and mechanism for actuating the main gear, said mechanism including a drive shaft, and means for supporting said shaft, said means including a standard of inverted V shape, and a bearing secured to one side of said standard.

24. Apparatus of the character described comprising, a screw, a main gear for actuating the screw and mechanism for actuating the main gear, said mechanism including a drive shaft, and a standard of inverted V shape for supporting said shaft.

25. Apparatus of the character described comprising, a screw, a main gear for actuating the screw and mechanism for actuating the main gear, said mechanism including a drive shaft, a power shaft, and means for supporting said shafts, said means including a standard of inverted V shape, and a pair of bearings secured to its sides.

26. Apparatus of the character described comprising, a screw, a main gear for actuating the screw and mechanism for actuating the main gear, said mechanism including a transmission gear, its shaft, a power gear meshing with the transmission gear for rotating the same, and clutch mechanism for engaging and disengaging the transmission gear with and from its shaft.

27. Apparatus of the character described comprising, a screw, a main gear for actuating the screw and mechanism for actuating the main gear, said mechanism including a transmission gear, its shaft, a power gear meshing with the transmission gear for rotating the same, said transmission gear having an elongated sleeve bearing on its shaft, and clutch mechanism for engaging and disengaging the transmission gear with and from its shaft.

28. Apparatus of the character described comprising, a screw, mechanism for actuating the screw, and means for supporting said screw and mechanism, said means including a main bed, and a pair of cross rails secured to the top of the bed and

projecting laterally therefrom to constitute a support for the driving motor.

29. In apparatus of the character described, a screw, a main pedestal for supporting the screw, a drive shaft, a bearing in the pedestal for one end of the drive shaft, an intermediate gear, a stub shaft mounted in the pedestal for supporting the intermediate gear, a plurality of sets of change speed gears, and shafts for said change speed gears, each shaft having an end journaled in the pedestal.

30. Apparatus of the character described comprising, a screw, a main gear for actuating the screw, a drive shaft, and intermediate gears for establishing connection be-

tween the main gear and the drive shaft, part of said intermediate gears being movable edgewise and part axially movable.

31. Apparatus of the character described comprising, a screw, a main gear for actuating the screw, a drive shaft, and intermediate gears for establishing connection between the main gear and the drive shaft, part of said intermediate gears being eccentrically mounted for edgewise movement and part being slidably mounted for axial movement.

In testimony, that I claim the foregoing as my invention, I have signed my name this second day of October, 1919.

VERNON ROYLE.
